UNITED STATES PATENT OFFICE

EDMUND C. MORGAN, LATE OF NEW YORK, N. Y.; OLIVE EUGENIE MORGAN EXECUTRIX OF SAID EDMUND C. MORGAN, DECEASED

LOADING MACHINE

Application filed December 8, 1917, Serial No. 206,259. Renewed November 30, 1925.

This invention relates to a machine for loading coal and other material and is especially adapted for loading material in mines.

3 The object of the invention is to provide a machine of the class named which shall be of improved construction and operation.

The invention is exemplified in the combination and arrangement of parts shown in 15 the accompanying drawings and described in the following specification, and it is more particularly pointed out in the appended claims.

In the drawings—

17 Fig. 1 is a top plan view of a loading machine illustrating one embodiment of the present invention.

Fig. 2 is a side elevation of the machine shown in Fig. 1.

20 Figs. 3, 4 and 5 together constitute a side elevation of the machine on a larger scale than that of Fig. 1.

Fig. 6 is a vertical sectional view on line 6—6 of Fig. 5.

25 Figs. 7, 8 and 9 together constitute a top plan view of the machine.

Fig. 10 is a horizontal sectional view taken just above the wheels of the rear truck.

29 Fig. 11 is a similar view of the forward truck.

Fig. 12 is a rear elevation of the machine.

Fig. 13 is a vertical sectional view on line 13—13 of Fig. 4.

35 Figs. 14 and 15 are diagrammatic elevational and bottom plan views respectively illustrating the pivotal arrangement of the receiver for the material to be loaded.

Fig. 16 is a diagrammatic view showing 40 a horizontal section through a mine chamber with the machine in operative position.

In some regions mining operations are carried on by first driving a series of parallel entries away from the mine opening for 45 a considerable distance leaving a series of ribs between the entries to support the mine roof. After the entries have been driven to the desired distance, the ribs are cut through at the outer ends of the entries and the coal 50 in the ribs is then removed by working back-

wardly toward the mouth of the mine. The final result of this method of operation is the removal of all of the coal from the mine vein, leaving the roof to settle in the rear of the operating position during the backward 55 working by which the ribs are removed. In Fig. 16, the machine, constituting one embodiment of the present invention, is shown in position for performing the return operation in the method of mining referred 60 to by which the ribs are removed. Although the machine is in no sense limited to this particular operation it is especially well adapted for working backwardly toward the material which is being removed and 65 toward the body portion of the machine.

The machine as a whole comprises three pivotally connected sections; the rear section designated by the letter A in the drawings is a conveyer section for discharging 70 the material into the car by which it is transported from the mine chamber; the middle section B carries the greater part of the operating mechanism for the machine and also has pivotally supported thereon the forward or receiving section C. The main or central section B comprises a frame 20 having front and rear uprights 21 and 22 respectively, which are connected at their lower ends by side bars 23 and at their upper ends by side 75 bars 24. The uprights 21 and 22 are slotted at 25 and 26 respectively, at their lower ends to form slideways for journal boxes 27 and 28. Springs 29 and 30 are interposed between the journal boxes and the upper ends 80 of their respective slots to provide a resilient support for the frame 20. Front and rear axles 31 and 32 are journaled in the boxes 27 and 28 respectively and are provided with track wheels 33. A plate 34 extends across 85 the bottom of the frame 20 between the lower edges of the side bars 23. A motor 35 is supported on the plate 34 and is provided with a pinion 36 (Fig. 11) driving a gear wheel 37 carried by a shaft 38 journaled in 90 bearings 39 which are carried by standards 40 (Fig. 13) mounted upon the plate 34. The standards 40 also carry a pair of bearings 41 (Fig. 11) in which the inner ends of shafts 42 and 43 are journaled. The outer ends of 95 100

these shafts are journaled in bearings 44 and 45 respectively, which are formed upon the upper edges of the side plates 23. The shaft 38 is provided at its outer ends with a pair of pinions 46 and 47 which mesh with gear wheels 48 and 49 carried by the shafts 42 and 43 respectively. The gears 48 and 49 may be clutched to their respective shafts by the friction clutches 50 and 51. The clutch 50 is operated by a rod 52 pivoted at 53 to the upper surface of the plate 34, and the clutch 51 is operated by a similar rod 54 pivoted at 55 to the plate 34. The rod 54, as shown in Fig. 11, is provided at its upper end with a threaded sleeve 56 which engages threads 57 on a rod 58 journaled in the side plates 23. The rod 58 is provided with a hand wheel 59 by which it is rotated to shift the clutch 51. The rod 52 is similarly connected with a rod 60 journaled in the upper bars 24 and provided with a hand wheel 61 (Fig. 4). Drums 62 and 63 (Fig. 11) are secured to the outer ends of the shafts 42 and 43 respectively, and are provided with cables 64 and 65 for a purpose to be described.

A conveyer frame 65' is pivotally mounted upon a rod 66 extending across the frame of the machine between the upper side plates 24, as shown in Figs. 4 and 8. The conveyer frame, as shown in Fig. 13, includes side plates 67 connected by a bed plate 68 and angle bars 69 which lie adjacent the outer edges of an endless flight conveyer 70 which travels upon the bed plate 68. Overhanging flanges 71 are connected with the plates 67 of the conveyer frame and overlie the chains of the conveyer 70. The conveyer 70 is driven by a motor 72 mounted on a plate 73 supported by the uprights 22. The motor 72 operates a shaft 74 through reduction gearing contained in a casing 75' and the shaft 74 is provided with sprocket wheels 75 which mesh with the chains of the conveyer 70. The upper end of the conveyer 70 passes over suitable sprocket wheels on the bar 66 while the lower end passes over similar sprockets on a shaft 76 at the forward end of the conveyer frame 65', as shown in Fig. 5 of the drawings.

At its forward end the conveyer frame 65' is curved outwardly to form a hopper 77, as shown in Figs. 5 and 9, and this hopper is provided with a downwardly projecting circular rim 78 which carries a flange 79 at its lower edge and which is surrounded by a circular band 80 by means of which the forward section C of the machine is pivotally supported upon the conveyer frame 65'. The band 80 carries a pair of bracket plates 81 to the inner surfaces of which are secured the side plates 82 of the conveyer frame which constitutes the main portion of the section C of the machine. The plates 82, as shown in Fig. 6, are connected by upper and lower bed plates 83 and 84 and a supplemental

plate 85 upon which the return run of the conveyer 86 travels. Overhanging flanges 88 protect the chains of the active run of the conveyer. As shown in Fig. 5 the conveyer 86 is driven by a motor 89 supported on a plate 90 secured to the bracket plates 81. The motor 89 drives a sprocket wheel 91 which meshes with the lower run of the conveyer and imparts movement thereto. Hinged to the outer faces of the horizontal portions of the side plates 82, at their upper edges, is a pair of swinging platforms 92 and 93, shown in Figs. 5, 6 and 9. The platform 92 is shown in its lowered position in Figs. 6 and 9 while the platform 93 is shown in its raised position. Detents 94 are provided for holding the platforms up when they are raised. In the rear of the plates which form the platforms 92 and 93, and in position to form extensions of these platforms, when lowered, is a pair of fixed inclined plates 95 and 96 which have their rear ends curved upwardly to form guard plates as shown at 97. It will be seen from Fig. 6 that the plate 93 in its uppermost position forms an upwardly and outwardly inclined sideboard for the conveyer 85. Removable plates 98 are provided to bridge the space between the ends of the plates 92 and 93 and the inclined walls 99 of the conveyer frame adjacent the bracket plates 81. The plates 98 are provided with pins 100 arranged to enter openings 101 to hold the removable side plates 98 in place. One of these plates is shown in place in Fig. 6 of the drawings. The plate for the opposite side will be similar to the one shown but will be reversed in contour to correspond to its position. The forward end of the conveyer frame is provided with a forwardly and downwardly inclined platform or nose piece 102 which is shaped at its outer ends as shown at 103 to form a continuation of the hinged platforms 92 and 93 when they are in their lowered position. The bracket plates 81 are provided with guide pulleys 104 and 105 for the cables 64 and 65 and a pair of eyes 106 and 107 are secured to the nose piece 102 at opposite sides of the conveyer for interchangeably receiving a guide pulley 108. It will be apparent from Figs. 9 and 16 that the receiving section C of the machine may be swung laterally by means of the cables 64 and 65, the direction of movement depending upon the particular cable used and the way in which it is arranged through the guide pulleys. To swing the receiving section in a clockwise direction, as viewed in Fig. 16, the cable 65 is employed and the guide pulley 108 is attached to the eye 107 and the cable passed through the pulley and attached to a fixed anchor on the side of the machine toward which it is desired to move the conveyer. When the cable is then wound upon its drum, it is apparent that the receiving section of

the machine will be swung in the desired direction. By a similar arrangement of the other cable, a reverse rotation of the section C may be accomplished. As shown in Figs. 5 14 and 15 the supporting ring 80 for the conveyer section C may be provided with lugs 110 arranged to contact with a stop 111 extending downwardly from the under surface of the conveyer section 65'. This arrangement limits the angular movement of the receiving section.

In view of the foregoing description of the apparatus embodied in applicant's structure as shown in the drawings, it will be evident 15 that the supporting framework constitutes a portable base unit upon which is mounted a conveyer pan C including a depressed forward end or nose portion having a back and forth sweep movement across the floor of the 20 mine, as illustrated in Fig. 16. Upon the marginal edges of the nose portion there are mounted downwardly and outwardly inclined surfaces, as shown at 92 and 93 in Fig. 6, it being understood that both of the 25 marginal edge scoops 92 and 93 may be in their floor contacting positions when desired. It should also be understood that the downwardly and outwardly inclined surfaces 92 and 93 have the inherent function of maintaining the nose portion beneath the material to be loaded and in engagement with the mine floor, thereby preventing the front or nose end of the machine from climbing the coal pile instead of forcing its way underneath it. By maintaining the bottom 84 of the nose portion of the conveyer pan on the floor surface the ring 80 will also be maintained in proper position to permit free rotation of the pan C with its rear end continuously in delivery communication with the hopper 77 throughout an angular movement of over 180°.

Mechanism is provided for raising and lowering the conveyer section 65' and the receiving portion C of the machine pivotally carried by the forward end of this conveyer section. This mechanism is illustrated in Figs. 4 and 11 and comprises a sleeve 112 loosely mounted on the axle 31 and carrying 45 an arm 113 to which a link 114 is pivotally connected. The link 114 has its upper end pivoted to a lug 115 extending downwardly from the under surface of the conveyer section 65'. The sleeve 112 and arm 113 are resiliently held in position to support the conveyer section 65' by a counterbalancing spring 116 having one end attached to the plate 34 and the other end attached to an arm 117 secured to the sleeve 112. Another 55 arm 118 is carried by the sleeve 112 and has a link 119 pivotally connected to the outer end thereof. The opposite end of the link 119 is pivoted to an arm 120 rigidly connected to a shaft 121 journaled in the side plates 23 of the machine frame. The shaft 121 carries

a lever 122 at its outer end by means of which the shaft may be rotated and a catch 123 is carried by the side plate 24 to hold the lever 122 in retracted position. When the lever 122 is drawn toward the catch 123 it is apparent that the arm 113 will be rocked upwardly to raise the conveyer section 65' and the mechanism supported thereon above the surface of the mine floor and into position to permit transportation of the machine 75 along the supporting track.

The rear or discharge section A of the machine includes a hopper 125 which is pivotally supported at 126 on a rearwardly extending bracket 127 carried by the frame 20 of the central section B. An upper bracket 128 is pivotally connected at 129 to a bar 130 secured to the upper portion of the hopper 125. This pivotal connection permits relative movement between the sections A and B to allow the machine to pass around sharp curves in the track over which it is transported. It is apparent that the conveyer 70 will discharge into the hopper 125 irrespective of the relative angular position of the two sections of the machine. The hopper 125 is continued rearwardly to form a conveyer frame 131 over which an endless flight conveyer 132 travels. The hopper and conveyer are supported by a truck frame comprising uprights 133 and 134 which are connected together at their lower ends by bars 135. The bars 135 are in turn connected by a cross plate 136, as shown in Fig. 10. The uprights 133 and 134 are provided with slide-ways 137 for journal boxes 138 which form bearings for the axles 139 of the truck. The axles 139 are provided with track wheels 140 which run upon the track 141 over which the machine travels. A motor 142 is pivotally supported at one side by straps 143 extending around the axle 139 and is resiliently supported at its opposite side by springs 144 surrounding an upright rod 145 carried by the cross plate 136. The motor 142 is arranged to rotate the axle 139 through gearing 146. The axles 139 are connected for rotation in unison with one another by a sprocket chain 147 and sprocket wheels 148. Brake-shoes 150 are arranged to bear upon the wheels 140 and are operated through suitable link mechanism by a lever 151 connected with a cross rod 152 and held in place by a toothed bar 153. By this brake mechanism the machine may be secured for movement along the track during the operation of the material handling mechanism.

The conveyer 132 is driven by a motor 154 which operates sprocket wheels 155 connected with the motor through gearing 156. The motor is supported between the uprights 133 by means of angle bars 157 extending transversely from one of the uprights to the other. The motor 154 is governed by a controller 158 secured to the conveyer frame 131 near

the discharge end thereof so that the operation of the conveyer may be regulated by an operator in the car 159 into which the material is discharged from the loading machine, and by means of which it is transported out of the mine chamber. The various other motors for operating the different parts of the machine are governed by a series of controllers 160 carried by the upper side plate 24 of the central section B.

In operating the machine to load coal that has been broken down at the outer ends of a pair of ribs in a mine chamber, as illustrated in Fig. 16, the machine is moved along the track to bring the receiving section C into a position adjacent the ends of the ribs being worked. In breaking the coal down portions of it will probably fall into the entry in which the machine is operated and this will be removed first by forcing the nose piece 102 beneath the material in front of the machine. This may be done either by driving the machine forwardly by the rotation of its track wheels, or by anchoring the cables 64 and 65 to fixed supports in front of the machine and then winding the cables upon their respective drums. During this operation the endless conveyers will, of course, be driven to carry the coal to the rear of the machine and discharge it into the car 159. After a passage has thus been opened of sufficient width to receive the receiving section C of the machine, the machine will be located, as shown in full lines in Fig. 16. The cable 65 may then be trained through the guide pulleys 105 and 108 and attached to an anchor, as shown at 165 in Fig. 16. The plate 92 is arranged in its lowered position while the plate 93 is swung upwardly and the removable plate 98 is placed in position to cooperate with the plate 93 to form a wall along the side of the conveyer opposite the receiving side 92. The cable 65 may now be wound upon its drum and the receiving section C of the conveyer will be swung in a clockwise direction, as viewed in Fig. 16, and the side of the conveyer section C will be forced beneath the loosened coal along substantially its entire length. As the receiving section is moved beneath the coal, the endless conveyer 86 will carry the coal rearwardly and upwardly and discharge it upon the conveyer of the central section B from whence it will be carried backwardly and loaded into the cars for transportation. As the loading operation progresses and the section C is swung farther about its pivotal support, the anchor for the cable 65 may be shifted, as indicated in broken lines in Fig. 16. When the receiving section C finally reaches a position at right angles to the main body of the machine, one of the lugs 110 will strike the stop 111 and prevent further rotary movement of the conveyer section. The operation will be continued, however, by further winding the cable 65 which will move the

entire machine along the track in a rearward direction and carry the conveyer section C backwardly with its receiving side at right angles to the direction of movement of the machine. Therefore as each successive portion of the ends of the pillars shown in Fig. 16 are dislodged by blasting or otherwise the receiving conveyer section C may be swung from an inclined position along horizontal lines to a right angle position as determined by the limit stop mechanism shown in Figs. 14 and 15. When the outer end of the rope is anchored and the limit stop mechanism prevents further swinging movement of the conveyer section C continued pull on the rope while the brake mechanism shown in Fig. 3 is released will cause the whole machine to move along the mine track and thus effect rectilinear movement of the receiver of the conveyer section C in a direction parallel to the mine track and along lines extending transversely of said receiver. The material scooped up by the digger 92 or 93 will be directed onto the endless conveyer of the receiver which conveyer is in central position and compact by reason of being composed of superposed portions adapted to travel in opposite directions. During this portion of the operation the brakes upon the track wheels will be released to permit the rearward movement of the machine. If desired the cable 164 may be employed to aid in the rearward movement of the machine, the arrangement of the cable for this purpose being indicated in Fig. 16. As shown in that view, the cable passes around its guide pulley 104 and is secured to an anchor 166 in the entry and in the rear of the pulley 104. After the loosened material on one side of the entry has all been collected, the operation is reversed and the receiving section C swung in the opposite direction to load the coal on the other side of the entry. In this way two adjacent ribs of the mine may be removed by operating from a single entry between the two.

The forward conveyor section C is adapted to rest on and slide over the mine floor as shown in Figs. 2 and 5. On account of the bottom 84 of the frame 82 being flat the conveyor section is moved along horizontal arcuate lines when swung about the hopper 77. An endless conveyor on the section C has superposed portions traveling in opposite directions as illustrated in dotted lines in Fig. 5. Such direction of travel is transversely of such horizontal lines. The upper receiving portion of the conveyor is in a horizontal plane as shown in Fig. 5. Extending along the lateral faces of the frame of the conveyor section C over the greater length thereof are scoops 92 and 93 (Figs. 1, 2 and 6) for directing material from the mine floor onto the upper horizontal receiving portion of the conveyor. By providing endless conveyor

mechanism having superposed portions traveling in opposite directions, the conveyor section may have the conveyor centrally located with the scoops arranged laterally as well as at the outer end.

In the co-pending application Serial No. 186,118, filed August 14, 1917, for an improvement in loading machines, there is described and claimed a structure for effecting loading of material from a mine floor in advance of a mine track by longitudinal movement of a whole machine along the mine track and by swinging movement laterally relatively to the mine track, but in such construction the scooping plane extends across the outer end of the gathering device and this gathering device must be moved into positions extending laterally from the forward end of the machine before lateral swinging movements are effected. The width of the scoop is limited by the width of the gathering device because the machine must travel along narrow entries, and therefore the capacity of loading by lateral swinging movements is limited. The structure shown in the present application is an improvement on that disclosed in Serial No. 186,118 in that the scooping means extends not only across the outer end of the gathering device, but also along both sides of the gathering device which is elongated as shown in Figs. 1 and 2. Consequently the relatively narrow scoop 102 may be used in a narrow entry when first beginning loading operations and the elongated lateral scoops 92 and 93 are effective in efficiently performing the operations illustrated in Fig. 16 for gathering and loading the material dislodged from the ends of the coal pillars as hereinbefore fully described.

Furthermore, in Serial No. 186,118 there is shown only two conveyers, while in the present application the conveyer apparatus is divided into three sections as shown at A, B and C in Figs. 1 and 2, the intermediate section being mounted on the forward truck frame while being confined against lateral movement but holding the forward hopper 77 central of the mine track while the gathering device C may perform the operations illustrated in Fig. 16. In Serial No. 186,118 there is also described and shown mechanism for elevating the gathering device for transportation, but such elevating mechanism is power-operated. In the present application as shown in Fig. 4, the lever 122 is connected to the section B so that the latter together with the gathering device C may be elevated above the plane of the track for transportation purposes. This operation may easily be effected by means of the lever 122 by reason of the presence of the counter-balancing mechanism shown at 116 in Figs. 4 and 11. When electric power is not available and it is desired to elevate the gathering device C for transportation by means of an electric loco-

5
motive coupled to the loading machine shown, the hand-operated mechanism may be relied on. Furthermore, the rope gearing arranged as shown in the present application is an improvement over the swinging rope gearing in Serial No. 186,118 in that in the latter the swinging movement is comparatively limited, whereas in the present application the swinging movements of the gathering device may extend through 180° as illustrated in Fig. 16.

Obviously those skilled in the art may make various changes in the construction and arrangement of parts without departing from the spirit and scope of the invention as defined by the claims hereto appended and therefore it is to be understood that the invention is not to be restricted to the precise construction herein disclosed.

Having thus fully disclosed an embodiment of the invention, what is desired to be secured by Letters Patent of the United States is:

1. In a loading machine, the combination with a conveyor frame adapted to slide over the surface of a mine floor along horizontal lines, of an endless conveyor mounted thereon having superposed portions traveling in opposite directions along said frame transversely of such horizontal lines, and having an upper receiving portion in a substantially horizontal plane, and means extending along the lateral face of said frame over the greater length thereof for directing material from the floor on to the upper horizontal receiving portion of said conveyor.

2. In a loading machine, the combination with a frame adapted to rest on and slide over the floor of a mine chamber, of an endless conveyor having superposed portions traveling in opposite directions and having an upper horizontal receiving portion extending laterally of said frame and adapted to travel longitudinally of said frame, scooping means extending along one of the lateral edges of said frame for directing dislodged material from the floor of the mine chamber onto the receiving portion of said conveyor, and means for moving said frame laterally to cause said scooping means to direct such dislodged material onto said conveyor.

3. In a loading machine, the combination with an elongated conveyor frame having a flat bottom adapted to rest on and slide over the floor of a mine chamber, of an endless traveling conveyor having superposed portions adapted to travel in opposite directions and having an upper horizontal receiving portion traveling rearwardly from the forward end of said elongated conveyor frame, an inclined plane extending from one of the lower lateral edges of said conveyor frame to one side of the receiving portion of said traveling conveyor to form a scoop having a width equal nearly to the entire length of that portion of said conveyor frame slid-

- ing over the floor in position to direct loose material on the floor on to the upper side of said conveyor along a path having a width equal nearly to the entire length of said conveyor frame, and means for sliding said conveyor frame laterally over the floor under dislodged material thereon to direct such material onto the upper rearwardly traveling portion of said endless conveyor.
10. In a loading machine, the combination with a supporting frame, of an elongated receiver having one end thereof pivotally connected with said frame for lateral movement relatively thereto, an inclined member extending along the lateral face of said receiver for nearly the whole length thereof, and means for swinging said receiver about its pivotal connection with said supporting frame to force said inclined member beneath dislodged material to cause the latter to be deposited on said receiver entirely within the boundary of the latter.
15. In a loading machine, the combination with a supporting frame, of an elongated receiver having one end thereof pivotally connected to said supporting frame in position to move over a mine floor in a substantially horizontal plane, an endless conveyer having superposed portions traveling in opposite directions lengthwise of said receiver, an inclined platform connected with the lateral side of said receiver and extending substantially the entire length thereof in position for directing dislodged material from 20 the floor of the mine chamber onto the upper side of said conveyer, and means for moving said receiver laterally to force said inclined platform beneath the dislodged material to direct the latter onto the upper side of said conveyer.
25. In a loading machine, the combination with an elongated receiver for material to be loaded from the floor of a mine chamber, of means for moving said receiver longitudinally thereof and also laterally thereof, means extending along the forward end of said receiver for directing material onto said receiver when the latter is moved longitudinally, and means extending along the greater portion of said receiver for directing dislodged material thereon from the floor of the mine chamber when said receiver is moved laterally.
30. In a loading machine, the combination with a supporting frame, of an elongated receiver having one end thereof pivotally connected with said frame for lateral movement relatively thereto, an inclined platform connected with the lateral side of said receiver and extending substantially the entire length thereof in position for directing dislodged material from 35 the floor of the mine chamber onto the upper side of said conveyer, and means for moving said receiver laterally to force said inclined platform beneath the dislodged material to direct the latter onto the upper side of said conveyer.
35. In a loading machine, the combination with a supporting frame, of an elongated receiver having one end thereof pivotally connected with said frame for lateral movement relatively thereto, an inclined platform connected with the lateral side of said receiver and extending substantially the entire length thereof in position for directing dislodged material from 40 the floor of the mine chamber onto the upper side of said conveyer, and means for moving said receiver laterally to force said inclined platform beneath the dislodged material to direct the latter onto the upper side of said conveyer.
45. In a loading machine, the combination with a supporting frame, of an elongated receiver having one end thereof pivotally connected with said frame for lateral movement relatively thereto, an inclined platform connected with the lateral side of said receiver and extending substantially the entire length thereof in position for directing dislodged material from 50 the floor of the mine chamber onto the upper side of said conveyer, and means for moving said receiver laterally to force said inclined platform beneath the dislodged material to direct the latter onto the upper side of said conveyer.
55. In a loading machine, the combination with a supporting frame, of an elongated receiver having one end thereof pivotally connected with said frame for lateral movement relatively thereto, an inclined platform connected with the lateral side of said receiver and extending substantially the entire length thereof in position for directing dislodged material from 60 the floor of the mine chamber onto the upper side of said conveyer, and means for moving said receiver laterally to force said inclined platform beneath the dislodged material to direct the latter onto the upper side of said conveyer.
65. In a loading machine, a frame, an elongated receiver having one end thereof connected with said frame, means for moving said receiver laterally and longitudinally, and means extending substantially around that portion of the periphery thereof in advance of said supporting frame for directing dislodged material onto said receiver both when said receiver is moved laterally and when moved longitudinally.
70. In a loading machine, the combination with a supporting frame, of an elongated receiver having one end thereof pivotally connected with said frame for lateral movement relatively thereto, an inclined platform connected with the lateral side of said receiver and extending substantially the entire length thereof in position for directing dislodged material from 75 the floor of the mine chamber onto the upper side of said conveyer, and means for moving said receiver laterally to force said inclined platform beneath the dislodged material to direct the latter onto the upper side of said conveyer.
75. In a loading machine, the combination with a receiver for material to be loaded, of a conveyor extending longitudinally of said receiver, a plate having an extended surface, and means for adjustably connecting said plate with one side of said receiver for movement into a downwardly inclined position to act as a scoop for directing material from a floor upwardly on to said receiver when the latter is moved laterally in a direction toward that side of said receiver to which said plate is connected, and for adjustably connecting said plate with said side of said receiver to occupy an upwardly extending position to form a side wall for said conveyor.
80. In a loading machine, an elongated conveyer frame for receiving material to be loaded, means for moving said frame laterally, and side plates pivoted to the lateral edges of said conveyer and movable into position to direct material onto said conveyer when said frame is laterally moved and also into position to form side walls for said conveyer.
85. In a loading machine, an elongated frame for receiving material to be loaded, a conveyer mounted on said frame, an inclined nose piece at one end of said frame for directing material onto said conveyer, means for moving said frame longitudinally to force said nose piece beneath material to be loaded, means for moving said frame laterally, and means, connected with the lateral faces of said frame and movable into and out of position to form inclined planes, for entering beneath material and directing said material onto said conveyer when said frame is moved laterally.
90. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
95. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
100. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
105. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
110. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
115. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
120. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
125. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.
130. In a loading machine, the combination with a supporting frame, of a receiver for material to be loaded pivotally connected to said frame for lateral arcuate movement relatively thereto horizontally over the floor of a mine chamber while substantially in sliding engagement with said floor, inclined plates adapted to be connected to the lateral edges of said receiver in positions inclining upwardly or downwardly in accordance with the direction of lateral movement of said receiver, and means for operating said receiver including arcuate lateral movement thereof relatively to said supporting frame to gather material to be loaded while the inclined plate on the advance lateral edge extends downwardly in scooping position.

and the inclined plate on the opposite edge extends upwardly in guard position.

13. In a loading machine, the combination with a supporting frame, of a receiver for material to be loaded pivotally mounted on said frame, means extending horizontally along the greater portion of the lateral edge of said receiver and having an upwardly inclined surface making an angle with the plane of the floor equal to or greater than the angle of repose of the material scooped by said means on to said receiver, and means for swinging said receiver on its pivotal connection with said supporting frame to force said scooping means under the material to be loaded and to cause such material to be directed over such inclined surface onto said receiver.

14. In a loading machine, the combination with a supporting frame, of a receiver connected to said supporting frame and adapted to extend laterally relatively thereto and having a flat bottom adapted to move over the floor of a mine chamber, means extending along the greater portion of one side of said receiver and comprising a surface inclined upwardly from the floor for directing dislodged material from such floor on to said receiver, and means for moving said receiver rectilinearly transversely of itself along such floor to cause said upwardly inclined surface to scoop up loose material on the floor and direct it on to said receiver.

15. In a loading machine, the combination with a supporting frame, of an elongated receiver having one end thereof connected to said frame, a conveyer carried by said receiver for transferring dislodged material from said receiver to said frame, said receiver having a horizontal portion extending over the greater part of its length in position to move over a mine floor and said conveyer having a horizontal portion extending along the horizontal part of said receiver, means for moving the receiver relatively to said frame, means at the lateral edge of said receiver for directing dislodged material from the floor of the mine chamber onto said conveyer when said receiver is moved transversely of itself, and means for moving said receiver rectilinearly transversely of itself to gather material from the floor of the mine chamber at one side of the forward end of said supporting frame.

16. In a loading machine, the combination with a supporting frame, of an elongated frame comprising a receiver pivotally connected to said supporting frame for angular adjustment relative thereto, means extending along one side of said receiver for substantially the entire length thereof for directing material onto said receiver, means for propelling said supporting frame, and means associated with said frame to co-act with said propelling means to move said

receiver rectilinearly while occupying a predetermined angular position relative to said frame and while said directing means moves under the material to be loaded.

17. In a loading machine, the combination with a supporting frame, of an elongated receiver connected to the front end of said frame in position to lie flat on the floor of a mine chamber and to move thereover, an endless conveyor comprising superposed portions adapted to travel in opposite directions to and from the outer end of said receiver with the upper rearwardly traveling portion occupying a position in an approximately horizontal plane a short distance above such floor, means extending along the greater portion of said receiver for entering material to pick up the same from the floor and direct it on to the upper horizontal rearwardly traveling portion of said conveyor, means for propelling said supporting frame rearwardly to effect rearward movement of the rear end of said receiver, and mechanism for moving the outer portion of said receiver rearwardly during the operation of said propelling means.

18. In a loading machine, the combination with an elongated supporting frame having wheels adapted to travel on a mine track, of an elongated receiver having a comparatively long outer horizontal portion and a comparatively short upwardly inclined portion at the outer end of said supporting frame, means extending along one of the sides of said elongated receiver for directing loose material from the floor onto said receiver, and means for swinging said receiver about a pivotal connection to said supporting frame to cause said directing means to enter loose material near one side of said track and collect such material on said receiver.

19. In a loading machine, the combination with a supporting frame having wheels adapted to travel on a mine track, of an elongated receiver pivotally connected to the forward end of said frame and having a long portion adapted to sweep over a mine floor near one side of said track and having a short portion inclined upwardly from said long portion toward said frame without extending across the latter, means connected with the sides of the long portion of said receiver for directing material from the floor on to said receiver when said receiver is moved laterally, and means for swinging said receiver in either direction on opposite sides of the track and adjacent thereto.

20. In a loading machine, a frame, an elongated receiver having one end thereof pivotally connected with the forward end of said frame, a conveyer carried by said receiver, means on the lateral edges of said receiver for directing material onto said conveyer when said receiver is swung about its axis to force one of the lateral edges thereof

into engagement with the material to be loaded, means for swinging said receiver about its pivotal connection with said frame into position at either side of said frame substantially at right angles to said frame, and means for moving said frame and receiver when so positioned in unison with one another in a rearward direction to force a lateral edge of said receiver into engagement with material to be loaded.

21. In a loading machine, the combination with a supporting frame, of a receiver pivotally connected to said frame for swinging movement relatively thereto, a cable adapted to have its free end anchored, means for guiding said cable from the outer end of said receiver to the anchorage, means at the other end of said receiver for guiding said cable along said receiver to said first-named guiding means or to an anchorage for the free end of said cable extending directly from the last-named anchorage to said second-named guiding means.

22. In a loading machine, a frame, a conveyer section having one end thereof pivotally connected with the forward end of said frame, means extending along the lateral edge of said conveyer section for directing material over said edge onto said conveyer, a winding drum on said frame, a cable arranged to be wound on said drum, and a guide pulley for said cable secured to the end of said conveyer section opposite its pivotal connection with said frame.

23. In a loading machine, a frame, a conveyer section for receiving material to be loaded having one end thereof pivotally connected with said frame, means extending along the lateral edges of said conveyer section adjustable into one position to guide material over said edges onto said conveyer and adjustable into another position to form side members for said conveyer, a pair of cables for swinging said conveyer section in opposite directions about its pivotal connection with said frame, guide pulleys for said conveyer on opposite sides thereof and adjacent the pivotal connection of said conveyer with said frame, and a guide pulley connected with the opposite end of said conveyer for selectively engaging said cables to cause said cables to swing said conveyer laterally in either direction.

24. In a loading machine, a conveyer section for receiving material to be loaded, said conveyer having side plates pivotally connected with the lateral edges thereof and movable into one position to guide material over said edges onto said conveyer and into another position to form side walls for said conveyer, and means for moving said conveyer laterally in either direction to force the side edges thereof into engagement with material to be loaded.

25. In a loading machine, a conveyer sec-

tion for receiving material to be loaded, side plates pivotally connected with the lateral edges of said conveyer and movable into one position to form inclined ways for guiding material onto said conveyer over the edges thereof and into another position to form side walls for said conveyer, an inclined nose piece for guiding material onto said conveyer over the front edge thereof, means for moving said conveyer section forwardly to force said nose piece into engagement with material to be loaded, and means for moving said conveyer section laterally in either direction to force the lateral edges of said conveyer into engagement with the material to be loaded.

26. In a loading machine, a conveyer section for receiving material to be loaded having a horizontally extending portion and an inclined portion, a fixed member for guiding material onto said conveyer over the lateral edge of the inclined portion thereof, and an adjustable member connected with the lateral edge of the horizontal portion of said conveyer section and movable into position to guide material onto said conveyer over said portion of the edge thereof.

27. In a loading machine, a conveyer section for receiving material to be loaded, means for guiding material onto said conveyer over the lateral edge thereof comprising a fixed and a movable portion, said movable portion being arranged to cooperate with said fixed portion when in one position, and removable means for cooperating with said movable portion to form a side wall for said conveyer when said movable portion is in another position.

28. In a loading machine, a conveyer section for receiving material to be loaded, means for guiding material onto said conveyer section over the lateral faces thereof comprising fixed incline members and adjustable side plates movable into position to cooperate with said incline members, said side plates being also movable into another position to form side walls for said conveyer section, and removable means for cooperating with said adjustable side plates when in position to form side walls for said conveyer to form a continuation of said side walls along the portion of said conveyer adjacent said fixed incline members.

29. In a loading machine, a main frame, a supplemental frame pivotally mounted on said main frame to swing vertically thereon, a conveyer carried by said supplemental frame and arranged to swing laterally relative thereto, mechanism for adjusting said supplemental frame and conveyer comprising a spring normally tending to raise said frame and conveyer but of a strength to permit said conveyer to contact with the surface upon which said machine operates, a lever for supplementing the action of said spring to raise said conveyer above said sur-

face, and a catch for holding said conveyer in its raised position.

30. In a loading machine, a frame, track wheels for propelling said frame over a track in a mine chamber, a horizontal receiving conveyer section pivotally connected with the forward end of said frame in position to move horizontally over the mine floor, power mechanism comprising rope winding mechanism for moving said frame forwardly to force the front portion of said receiving conveyer into material in front of said frame while said receiving conveyer is held in one position relative to said frame, means for swinging said receiving conveyer laterally to cause the lateral edge of said receiving conveyer to enter material at one side of the axis of said frame, and means for moving said receiving conveyer and frame backwardly in unison with one another into engagement with material at one side of said frame.

31. In a loading machine, a frame, a receiving conveyer pivotally mounted at the forward end of said frame to swing laterally, means arranged at the lateral edge of said conveyer to enter material to be loaded and to direct said material onto said conveyer, means for swinging said conveyor about its pivotal connection to the side of said frame, a stop for limiting the angular movement of said conveyer to cause said conveyer swinging means to move said receiving section and frame laterally in unison with one another when said receiving section has reached its limit of pivotal movement.

32. In a loading machine, the combination with a supporting frame, of a horizontally elongated conveyer frame, means for connecting said conveyer frame to said supporting frame to hold said conveyer frame for horizontal movement over a mine floor, scooping extensions along the sides and outer end of said conveyer frame, means for moving the conveyer frame longitudinally and laterally to gather material from the said mine floor, and a conveyer mounted on said conveyer frame to travel horizontally along the elongated portion thereof.

33. In a loading machine, the combination with a main frame, of a supplemental frame pivoted thereto and extending radially from such pivot to form an elongated receiver frame adapted to slide over a mine floor, inclined scooping extensions at the sides and outer end of said elongated receiver frame, a hopper on the main frame concentric with said pivot, an endless conveyer having an upper horizontal receiving portion extending along said elongated receiver frame and an upwardly inclined portion extending rearwardly to said hopper to deliver material to the latter, and means for swinging said supplemental frame horizontally to gather material.

34. In a loading machine, the combination

with a main frame, of a hopper at the forward end thereof in a low position, of a supplemental frame pivotally connected to said hopper and extending radially therefrom to form an elongated receiving frame, means at the lateral edges of the last named frame for scooping material on the floor onto said receiving frame, a conveyer extending along said receiving frame and thence to said hopper, means for swinging said receiving frame arcuately and horizontally while said conveyer maintains delivery communication with said hopper, and means for limiting the angular swing of said supplemental frame relatively to said main frame.

35. In a loading machine, the combination with a truck, of a conveyer mounted thereon, a deep hopper at the front end of said conveyer, an additional truck, an additional conveyer mounted on said additional truck, an additional hopper in a low position at the forward end of said additional conveyer, a pivotal connection between said deep hopper and said additional truck in position for said additional conveyer to have delivery communication with said deep hopper, a receiver conveyer pivotally connected to said low hopper and in delivery communication with the latter throughout a range of approximately 180 degrees, scooping means at the sides of said receiver conveyer, means for swinging said receiver conveyer laterally to cause said scooping means to gather dislodged material from the floor of a mine chamber in advance and at the sides of the forward end of the track on which said trucks are mounted, and means for lifting said low hopper and said receiving conveyer relatively to said additional truck to cause said receiving conveyer to clear the track and permit transportation of the machine.

36. In a loading machine, the combination with a horizontally elongated conveyer frame adapted to move over the surface of a mine floor along horizontal lines, of an endless conveyer mounted thereon and having superposed portions adapted to travel in opposite directions along said frame and having an upper receiving portion in a substantially horizontal plane, and a digger extending along one side of said frame parallel to the path of travel of the upper horizontal receiving portion of said conveyer.

37. In a loading machine, the combination with a supporting frame, of a scoop frame having a flat bottom adapted to move over a mine floor and having inclined surfaces at the outer end thereof and on both sides thereof for directing material from the floor onto the scoop, and endless conveyer mechanism mounted in the scoop and having superposed portions adapted to travel in opposite directions with the upper portion traveling rearwardly from the outer end of the scoop along substantially horizontal lines.

38. In a loading machine, the combination with a supporting frame, of a receiver pivotally connected to said frame for swinging movement relatively thereto, and mechanism comprising two cables one extending from the outer end of said receiver to an anchorage and the other extending from the inner portion of said receiver to another anchorage to effect the swinging of said receiver to gather material from a mine floor intermediate the ends of said receiver.

39. In a loading machine, the combination with a supporting frame, of a receiver pivotally connected to said frame for swinging movement relatively thereto over a mine floor, a cable adapted to have its free end anchored, means for guiding said cable from the outer end of said receiver to the anchorage, an additional cable, means at the inner portion of said receiver for guiding said additional cable to another anchorage, and winding mechanism for exerting pulls on said cables to swing said receiver laterally and cause material to be gathered thereon from the floor of the mine chamber.

40. In a loading machine, the combination with a track-mounted supporting frame, of a horizontally elongated conveyor section pivotally connected to the forward end of said frame in position to move over the mine floor, an elongated inclined scoop extending along one side of said conveyor section in position to direct material from the floor into said section, means comprising rope winding mechanism on said supporting frame and a rope directed along said conveyor section and from the outer end thereof to an anchorage extraneous to the mechanism for swinging said conveyor section relatively to said supporting frame and causing said inclined scoop to gather material from the floor onto said conveyor section, and means for operating said rope winding mechanism.

41. In a loading machine, the combination with a supporting frame, of an elongated rectangular receiver having one end thereof pivotally connected to said frame for lateral movement relatively thereto, a substantially rectilinear scoop inclined downwardly from one side of said receiver to the surface from which the material is to be loaded, means for swinging said receiver about its pivotal connection with said supporting frame to force said inclined scoop beneath the material on said surface to cause the latter to be deposited on said receiver entirely within the boundary of the latter, and a traveling conveyor within the rectangular area of said receiver and comprising superposed portions traveling in opposite directions to transfer toward loading position the material gathered by said scoop.

42. In a loading machine, the combination with an elongated receiver for material to be loaded from the floor of a mine chamber, of

means for moving said receiver longitudinally thereof and also laterally thereof, means extending rectilinearly across the end of said receiver and inclined downwardly to the floor for directing the material from the latter onto said receiver when the latter is moved longitudinally, and means extending rectilinearly along said receiver and inclined to the floor for directing dislodged material from the floor into said receiver when the latter is moved laterally.

43. In a loading machine, the combination with a wheeled supporting frame adapted to travel on a mine track, of an elongated receiver having one end pivotally connected to said frame, means comprising rope winding mechanism and a rope directed along said receiver to a fixed anchorage extraneous to the machine to swing said receiver on its pivotal connection to said frame, a scoop extending along one side of said receiver and inclined downwardly to the surface from which the material is to be loaded, and stops for limiting such swinging movement and holding the said receiver in predetermined relation to said frame to effect movement of the said receiver parallel to the mine track.

44. In a loading machine, the combination with a supporting frame, of an elongated gathering device comprising a receiver pivoted to said frame to swing laterally relatively thereto through an angle of about 180°, inclined elongated scoops extending along both sides of said receiver to direct material onto said receiver from the surface from which the material is to be loaded whether the gathering device is swung in one direction or the opposite, rope winding mechanism, ropes extending therefrom to anchorages extraneous to the machine, means for operating said rope winding mechanism to effect swinging of said gathering device in either direction from a position at right angles to the path of the machine at one side thereof to a similar position at the opposite side thereof, and loading apparatus extending from said receiver to and along said supporting frame.

45. In a loading machine, the combination with a supporting frame, of a horizontally elongated conveyor frame, means connecting said conveyor frame for horizontal movement over a mine floor at both sides of an entry back of working faces, scooping extensions along the sides of said conveyor frame, means for moving said conveyor frame laterally to positions at right angles to the path of the machine to gather material dislodged from said working faces, and loading mechanism comprising a conveyor mounted on said conveyor frame to travel horizontally along the elongated portion thereof.

46. In a loading machine, the combination with a supporting frame, of a receiver piv-

oted thereto and having an elongated portion extending along the surface from which the material is to be loaded, means for moving said receiver in the directions of said elongated portion and also laterally in opposite directions, inclined platforms extending along the sides of said receiver and across the forward end thereof in position to direct material from said surface onto said receiver,

10 and a traveling conveyor on said receiver.

47. In loading apparatus, the combination with a supporting frame, of an elongated rectangular receiver adapted to move over the surface from which the material is to be loaded, a pivotal connection between said receiver and said frame, inclined scoops along the sides of said receiver and across the forward end thereof, means for moving the receiver forward to gather a load, means for moving the receiver laterally to gather loads, and a traveling conveyor on said receiver.

48. In a loading machine, the combination with a frame adapted to slide over a mine floor, of adjustable plates connected to the sides of said frame to occupy downwardly inclined scooping positions or upwardly inclined receiving positions, and means for moving said frame over the mine floor in opposite directions to gather material therefrom while said plates are in their adjusted positions.

49. In a loading machine, the combination with a supporting frame adapted to travel on a mine track, of a gathering device connected to the forward end of said frame for operation in advance of the mine track, a scoop at the forward end of said gathering device to scoop up material when said frame is moved along a mine track, adjustable gathering plates extending along the sides of said gathering device to occupy either scooping positions or supporting positions, and means for swinging said gathering device laterally to effect the gathering of material by means of said gathering plates from the space in advance of the mine track.

50. In a loading machine, the combination with a supporting frame, of a gathering device comprising an inclined nose portion adapted to scoop material from the floor in advance of the mine track, means moving the supporting frame to operate said gathering device, and adjustable plates at the sides of the gathering device and both in upwardly inclined position to act as supports for the material when said frame is moved to effect the operation of said gathering device.

51. In a loading machine, the combination with a supporting frame adapted to travel on a mine track, of a receiver extending from the forward end of said frame along the surface in advance of the mine track, an inclined nose portion extending across the forward end of said receiver in position to scoop material from such surface, means for mov-

ing said supporting frame along the mine track to gather material from such surface, a traveling conveyer extending from said nose portion rearwardly along said receiver, and adjustable inclined walls extending upwardly from the side portions of said receiver to receive the scooped up material and direct it to said conveyer.

52. In a loading machine, the combination with a supporting frame, of a supplemental frame pivoted thereto to swing laterally relatively thereto, a conveyer on said supplemental frame, plates pivoted to the sides of said supplemental frame to occupy either downwardly inclined scooping positons or upwardly inclined supporting positons at the sides of said conveyer, means for holding the pivoted plates in their upwardly inclined positons, and mechanism for swinging the supplemental frame laterally to cause one of said plates to scoop up material onto said conveyer while the other plate acts to support material and confine it to said conveyer.

53. In a loading machine, the combination with a portable frame, of a gathering unit comprising an inclined scooping nose portion across its forward end, plates pivoted to the sides of said gathering unit and each adapted to occupy a downwardly inclined scooping position, means for moving the said frame longitudinally to operate the scooping nose portion, and means for moving the gathering unit laterally to cause one of said plates to act to scoop up material when in a downwardly inclined position.

54. In loading apparatus, the combination with a supporting frame, of a gathering unit connected thereto, an adjustable plate extending along one side of said gathering unit and adapted to occupy either a downwardly inclined scooping position or an upwardly inclined supporting and directing position, and means for operating said gathering unit to cause said plate when in its downwardly inclined position to scoop up material onto said gathering unit.

In testimony whereof I have signed my name to this specification, on this 5th day of December, A. D. 1917.

EDMUND C. MORGAN. 115
